UNITED STATES PATENT OFFICE.

JAMES TROTTER, OF CHICAGO, ILLINOIS.

DRAFT-REGULATING DEVICE FOR LOCOMOTIVES.

1,268,300.

Specification of Letters Patent.

Patented June 4, 1918.

Application filed July 27, 1916. Serial No. 111,548.

To all whom it may concern:

Be it known that I, JAMES TROTTER, a citizen of the United States, residing at Chicago, in the county of Cook and State of Illinois, have invented certain new and useful Improvements in Draft-Regulating Devices for Locomotives, of which the following is a specification.

This invention relates to improvements in draft regulating devices for locomotives, and one of the objects of the same is to provide an improved device of this character, by means of which a perfect draft condition and a uniform draft through all of the flues will be obtained, whereby an even depth of fire-bed will be maintained and the grate will be evenly covered throughout its entire area.

A further object is to provide an improved device of this character embodying a variable exhaust nozzle discharging into the stack and having means whereby the draft produced by the jet of exhaust steam from the cylinders will be at all times under the control of the engineer, so that the engineer may increase or decrease the velocity of the steam jet at will.

A further object is to provide an improved device of this character embodying an exhaust nozzle and a deflector adjustably mounted in the nozzle and means whereby the deflector may be adjusted at will to vary the size of space between the nozzle wall and the deflector and thereby vary the velocity of the steam, whereby the draft on the fire will be at all times under the control of the operator.

A further object is to provide improved means for arresting the sparks and cinders entrained by the steam as it is discharged from the nozzle into the stack.

To the attainment of these ends and the accomplishment of other new and useful objects as will appear, the invention consists in the features of novelty in substantially the construction, combination and arrangement of the several parts hereinafter more fully described and claimed and illustrated in the accompanying drawings in which:

Figure 1 is a vertical longitudinal sectional view of the front end of a locomotive

engine boiler constructed in accordance with the principles of this invention and as taken on line 1—1, Fig. 2.

Fig. 2 is a sectional view as taken on line 2—2, Fig. 1.

Fig. 3 is a horizontal sectional view as taken on line 3—3, Fig. 1.

Fig. 4 is a vertical sectional view taken on line 4—4, Fig. 1.

Fig. 5 is a vertical sectional view as taken on line 5—5, Fig. 6, of the exhaust nozzle showing the deflector in position therein.

Fig. 6 is a sectional view taken on line 6—6, Fig. 5.

Fig. 7 is a top plan view of the parts shown in Fig. 5.

Fig. 8 is a detail perspective view of a portion of the deflector and the operating member therefor, the parts being separated.

Referring more particularly to the drawings and in the present exemplification of this invention, the numeral 10 designates the smoke box or front end of a locomotive, which may be of any well known construction and into which the fire tubes or flues 11 discharge. Discharging into the smoke box 10 is a nozzle 12 which is located in a direct line with the stack 13, the latter communicating with the smoke box 10 in the usual manner. The exhaust steam from the engine cylinder is directed to the nozzle 12 in the ordinary and well known manner and is discharged from the nozzle directly into the stack.

An imperforate partition 14 is arranged within the smoke box in any suitable manner preferably by securing it along one edge 15 to the wall 16, just above the forward ends of the flues or tubes 11. This partition preferably embodies a short forwardly projecting portion 17 and a forwardly and downwardly inclined portion, from which projects a plate or table 18. This plate or table extends across the forward ends of the upper series of tubes 11 so that gases therefrom are deflected downwardly. The free end of the plate or table is supported in any suitable manner preferably by means of a cross bar 19 secured in position in any suitable manner; and the plate or table is provided with an enlarged opening or aperture 20.

- which is located above the end of the nozzle 12 and is of a diameter somewhat larger than the upper end 21 of the nozzle which end projects through the opening 20, so as to terminate a short distance above the plate 18. The free end of the plate or table extends forwardly beyond the nozzle 12 and terminates short of the forward end of the smoke box 10.
- 10 A suitable screen 22 in the form of a foraminous plate extends across the smoke box with one end thereof secured to the free end of the table or plate 18 and the other end is preferably secured to the top of the smoke box 10 adjacent the forward end thereof. The partition 14, the plate or table 18 and the screen 22 are so arranged as to divide the smoke stack into two compartments, one preferable above the other and 15 secured adjacent the plate or table 18 in advance of the nozzle is a downwardly extending inclined baffle plate 23 which extends in a direction away from the nozzle and terminates short of the bottom of the box.
- 20 If desired the screen 22 may be provided with a removable section 24 which may be held in position in any desired or suitable manner.

Surrounding the end of the nozzle 12 is 30 a plate 25 which is provided with an aperture 26 through which the end of the nozzle passes and this end may be provided with a flange or shoulder 27 against which the plate 25 rests. The plate is secured in position in any suitable manner 35 preferably by means of fastening devices 28 which secure the plate to the plate 19.

This plate 25 is provided with perforations 30 therethrough which perforations 40 surround the end of the nozzle, and the area of the perforations 30 in the plate 25 is equal to the area of the choke of the stack. This perforated plate 25 permits a proper action 45 of the draft on the fire through the medium of the perforations 30, which latter restrict the passage of the gases through the plate 18 and perforations 25. As a result a portion of the gases will be forced to travel around the front end of the smoke box 10 50 and through the screen 22, before they can be entrained into the stack 13. The screen 25 also prevents the cinders and sparks, which have been drawn through the flues 11 from being carried directly into the stack 55 18 by the steam or vapor discharged through the nozzle 12. As the steam from the cylinder discharges into the stack 13 the air in the smoke box will become rarefied and will be drawn up through the stack, thereby producing a draft through the pipes or flues 11.

A petticoat pipe 31 having a flanged lower extremity 32 is adjustably secured to a suitable support 33 and is located intermediate the nozzle 12 and the stack 13 and in a direct line with the discharge end of the nozzle so

that the steam passing from the nozzle also passes through the pipe 31 before entering the stack. If desired an adjustable section 34 may be provided on the pipe 31.

Arranged above the plate 18 and between the plate and the stack 13 is a chamber having imperforate side and end walls 35, 36, the bottom of the chamber being formed by a portion of the plate 18 and the perforated plate 25. The top 37 of the chamber is provided with an opening 38 having a flange therearound which flange telescopes with the bottom of the stack 13 so that the opening 38 will be in direct line with the nozzle 12 and the stack 13.

The side walls 35 of the chamber are spaced for a considerable distance from the adjacent sides of the smoke box, and a plate 40 having a portion thereof cut away is provided so as to close the space between the chamber formed by the walls 35, 36, 37, and the bottom plate 18 to close said space to the passage of gases thereto from the front of the smoke box. The cutaway portion of the plate 40 coincides with the opening 41 formed through the front wall of the chamber and this plate 40 is held in position in any suitable manner preferably by being secured to a flange 42 connected to the wall of the smoke box. Thus it will be seen that when the smoke and gases fill the smoke box, the portion thereof which does not pass through the screen 25 will pass through the screen 22 and be entrained into the stack 13.

In order that the draft produced by the exhaust steam, may be at all times under the control of the engineer, an adjustable deflector is provided and is arranged within the end of the nozzle 12, near the mouth thereof and comprises two complementary tapering sections 43, the sides of which overlap to form a substantially hollow conical deflector. The outer face of the deflector forms the inner wall of the annular steam passage and is substantially continuous, and the space between the sections of the deflector will be closed against the passage of steam therethrough in any position of the sections with respect to each other as the steam passes through the nozzle. One side 115 of each of the sections is substantially straight as at 44 and the other side is curved or arranged in cross section so that when the two sections 43 are assembled, there will be formed an annular space 46 between the inner wall of the extension 21 of the nozzle and the outer face or periphery of the deflector. The deflector is disposed within the nozzle and is spaced from the top of the nozzle so that an annular column of steam 120 will be maintained as the steam passes from the nozzle.

It will thus be seen that steam being discharged from the nozzle 12 will strike the deflector and be directed into the annular 125

space 46, and from the nozzle the steam will be discharged in a hollow column into the stack 13.

By adjusting the sections of the deflector 5 with respect to each other, the size of the space 46 may be enlarged or decreased at the will of the operator and by the enlarging or decreasing of this space, the velocity of the steam jet which acts upon the fire may be 10 varied, and while the velocity of the steam jet may be increased or diminished the area of entrainment will remain substantially the same.

Any suitable means may be provided for 15 supporting and adjusting the sections 43 of the deflector. A simple and effective construction embodies a hollow shaft 47 which is journaled in a suitable bearing 48 and is provided with an extremity 49 which is 20 angular in cross section and this extremity 49 passes into an angular opening 50 in a hub or enlargement 51 of the section 43. To the free end of the shaft 47 is connected an arm 52. These two sections 43 are 25 constructed and supported in the same manner and operate in opposition to each other.

The shafts are supported by means of a tie rod 53 which passes through the shafts, hubs 51 and through the ends of the arms 52 30 and is secured in position by means of suitable nuts 54 threaded upon the ends of the rod.

The arms 52 are arranged on the outside 35 of the extension 21 of the nozzle and connected with each of the arms is a link 55, the other end of the link being connected by a cross bar or lever 56. This lever 56 is in turn connected with an upright shaft 57, which is journaled at one end in a bearing 40 58 within the smoke box and passes through a suitable bearing 59, in the top of the smoke box. To the free end of the shaft 57 is connected an arm 60 and this arm 60 is connected with suitable operating mechanism 45 arranged in a convenient position for the engineer.

With this construction, it will be noted 50 that the shaft 57 when it is rotated will shift the lever 56 and as the ends of the lever move in opposite directions and are connected with the links 55, it will be manifest that the sections 43 of the deflector will be shifted toward or away from each other by the operation of the shaft 57, so that the 55 engineer may vary at will the size of the annular space 46 and thereby vary the velocity of the steam jet.

What is claimed as new is:

1. An exhaust nozzle embodying a hollow body, and an expansible and contractible deflector for the steam arranged in the nozzle below the top of the nozzle and spaced from the wall thereof to form an annular passage for the steam, said deflector embodying coöperating pivotally mounted

sections, said sections being shaped to maintain a substantially continuous circumferential outer face, the space between the parts of the deflector being maintained closed against the passage of steam therethrough, 70 in any position of the parts with respect to each other.

2. An exhaust nozzle embodying a hollow body, an expansible and contractible deflector for the steam arranged within the nozzle below the top of the nozzle and spaced from the wall thereof to form an annular passage for the steam, and means for expanding and contracting said deflector at will, said deflector embodying pivotally 75 coöperating sections constructed to maintain a substantially continuous circumferential outer face, the space between the parts of the deflector being maintained closed against the passage of steam therethrough, 80 85 in any position of the parts with respect to each other.

3. An exhaust nozzle embodying a hollow body, an expansible and contractible deflector for the steam arranged within the nozzle below the top of the nozzle and spaced from the wall thereof to form an annular passage for the steam, and means for expanding and contracting said deflector at will from a point remote from the nozzle, 90 said deflector embodying coöperating pivotally mounted sections constructed to maintain a substantially continuous circumferential outer face, the space between the parts of the deflector being also maintained 95 closed against the passage of steam therethrough in any position of the parts of the deflector with respect to each other.

4. An exhaust nozzle embodying a hollow body, and a deflector for the steam, arranged within the nozzle and below the top thereof, said deflector embodying two pivotally mounted complementary sections mounted for adjustment one with relation to the other and with respect to the nozzle, 105 and forming with the wall of the nozzle an annular passage for the steam, said deflector being variable in size and embodying means for maintaining a substantially continuous circumferential outer face, the 110 space between the sections of the deflector being maintained closed against the passage of steam therethrough during the passage of the steam through the nozzle.

5. An exhaust nozzle embodying a hollow body, and a deflector for the steam arranged within the nozzle below the top thereof and forming with the wall of the nozzle an annular passage for the steam, said deflector being variable in size and embodying two 115 pivotally mounted complementary sections mounted for adjustment in opposition to each other, and means for adjusting the sections at will, said sections embodying means for maintaining a substantially continuous 120 125 130

circumferential outer face to the deflector, and also for maintaining the space between the sections of the deflector closed against the passage of steam therethrough during the passage of the steam through the nozzle.

6. An exhaust nozzle embodying a hollow body and an adjustably mounted inverted frusto-conical shaped deflector for the steam, arranged within the nozzle and below the top thereof, said deflector itself embodying pivotally connected sections and being variable in size, said sections embodying means for maintaining the outer circumferential face of the deflector substantially continuous and the space between the parts of the deflector closed against the passage of steam therethrough during the passage of the steam through the nozzle.

7. An exhaust nozzle embodying a hollow body, and an adjustably mounted inverted frusto-conical shaped deflector for the steam arranged within the nozzle, said deflector embodying complementary sections pivotally connected for relative adjustment.

8. An exhaust nozzle embodying a hollow body, an adjustably mounted inverted frusto-conical shaped deflector for the steam arranged within the nozzle, said deflector embodying complementary sections pivotally connected for relative adjustment, and means for moving the sections about their pivot from a remote point.

9. An exhaust nozzle embodying a hollow body, an adjustably mounted inverted frusto-conical shaped deflector for the steam arranged within the nozzle, said deflector embodying complementary sections pivotally connected for relative adjustment, and means for moving the sections about their pivot and in opposition to each other at will.

10. An exhaust nozzle embodying a hollow

body, an adjustable inverted conically shaped deflector for the steam arranged within and below the top of the nozzle, said deflector embodying complementary sections mounted for pivotal movement with respect to each other, and means for swinging said sections about their pivot toward and away from each other, at will.

11. An exhaust nozzle embodying a hollow body, an adjustable inverted conically shaped deflector for the steam arranged within the nozzle, said deflector embodying complementary sections mounted for pivotal movement with respect to each other, a separate shaft detachably engaging each of said sections, a bearing for each of the shafts, means for tying the shafts and sections together, and means for rocking the shafts to move the sections in opposition to each other.

12. An exhaust nozzle embodying a hollow body, an adjustable inverted conically shaped deflector for the steam arranged within the nozzle, said deflector embodying complementary sections mounted for pivotal movement with respect to each other, a separate shaft detachably engaging each of said sections, a bearing for each of the shafts, means for tying the shafts and sections together, and means for simultaneously rocking the shafts to move the sections relatively to each other at will and from a point remote from the nozzle.

In testimony whereof I have signed my name to this specification in the presence of two subscribing witnesses, on this 24th day of July, A. D. 1916.

JAMES TROTTER.
